UNITED STATES PATENT OFFICE.

WILLIAM H. WETHERILL, OF PHILADELPHIA, PENNSYLVANIA.

CORRODING-HOUSE FOR THE MANUFACTURE OF WHITE LEAD BY THE OLD DUTCH PROCESS.

SPECIFICATION forming part of Letters Patent No. 252,823, dated January 24, 1882.

Application filed September 29, 1881. (No model.)

To all whom it may concern:

Be it known that I, WILLIAM H. WETHERILL, of the city and county of Philadelphia, and State of Pennsylvania, have invented a new and useful Improvement in the Construction of Corroding-Houses, of which the following is a full, clear, and exact description.

My improvements relate to the buildings or houses used in the production of lead carbonates by the old Dutch process of corrosion, which houses have heretofore been constructed of wood, and are expensive both in first cost and in maintenance on account of their rapid decay.

15 The invention consists in a permanent structure of stone or brick constructed to facilitate the process, as hereinafter described and claimed.

Reference is to be had to the accompanying drawings, forming part of this specification, in which similar letters of reference indicate corresponding parts in both the figures.

Figure 1 is a side elevation of a corroding-house of the improved construction, and Fig. 25 2 is a vertical section of the same.

The house is made in square form, preferably, of suitable height and size, and the foundations are placed so that the lower portion of the inclosed space is below the ground-level. 30 The sides or walls A are built of brick or stone of suitable thickness, and are sloped on the outside, so as to gradually reduce the thickness toward the top. In two opposite sides openings a are formed for use as passage-ways in building up the stack. The sides of these openings a are formed with rabbets on the interior to receive boards b, that are placed to close the passage, and sustain the banking. The rabbets allow wider banking at these necessary 40 more exposed localities. The foundation is sloped at the bottom of the openings a, as shown at c, so that air may have access be-

low the ground-level. The walls A are formed with numerous perforations at suitable distances apart. These are equally distributed, 45 and are of a size to secure ample ventilation. At the center of the house is a ventilating-flue pipe, d, extending from the floor to and through the roof e, and apertured at intervals to allow entrance of heated air to the pipe.

50 The roof e of the building may be of any suitable construction.

The building constructed as described is less expensive in first cost than the wooden buildings usually employed, and being indestructible by ordinary use, the expense of repairs is trifling. It is also superior in the respect of maintaining equality of temperature at all seasons of the year, and for that purpose less banking is required between the corroding-pots and the walls, thus giving more 55 available space.

In the process the pots and lead are stacked in the house and banked up with tan in the usual manner. The boards b are put in as the 60 stack is built up. The slopes c at the base of the openings allow inlet of air below the ground-level to take the place of hot air escaping by ventilator d.

Having thus described my invention, I claim 70 as new and desire to secure by Letters Patent—

An improved corroding-house having sloping walls of masonry, provided with numerous perforations, and with vertical openings a in two opposite sides, extending from the floor 75 to the roof, and having their inner sides rabbed to receive the ends of the boards b, and provided with a central perforated ventilating-flue, d, substantially as herein shown and described.

WILLIAM HENRY WETHERILL.
